3 Claims. (Cl. 46—120)

1

This invention relates to a mechanism for providing a mechanical display and more particularly to a mechanism for providing motion to a model of a human form.

It is an object of this invention to provide a mannequin for display purposes which as life-like motions.

It is another object of this invention to provide mechanism for actuating a doll to produce motions in the doll.

It is a further object of this invention to provide mechanism for actuating motion in a mannequin which is suitable for an advertising display.

It is a still further object of this invention to provide an animated doll having a mechanism which is simple in construction and reliable in operation.

These and other objects of this invention will be more fully understood upon consideration of the following description taken together with the accompanying drawings in which:

Fig. 1 is a front elevation of the mannequin actuating mechanism of this invention showing the mannequin partly in section;

Fig. 2 is a horizontal section of the mannequin of Fig. 1 taken on line 2—2 in the direction of the arrows;

Fig. 3 is a detailed view in vertical section of a part of the actuating mechanism seen from the rear;

Fig. 4 is a horizontal section taken on line 4—4 of Fig. 3 in the direction of the arrows;

Fig. 5 is a horizontal section of Fig. 3 taken on line 5—5 in the direction of the arrows;

Fig. 6 is a top view of the slide assembly of the actuating mechanism;

Fig. 7 is an elevational view of the slide assembly of Fig. 6 partly in section on line 7—7 of Fig. 6 taken in the direction of the arrows, and

Fig. 8 is a perspective view of the cruciform member of the slide assembly.

This invention involves the actuation of a dummy or mannequin made up of a flexible material and having a hollow interior which contains the actuating mechanism. The mannequin is suitably supported and the mechanism is driven from a motor source, either in said support or at some other location and the power is delivered to the mechanism in the mannequin by suitable covert means. The actuating mechanism contained within the mannequin is centered around a crank linkage supported on a stand and rotated by a shaft which delivers the power from the motor source. The linkage supports a sliding assembly which oscillates with the reciprocating motion of the linkage as it is rotated by the shaft. The sliding assembly is made up of an integral base having a slotted center and on its horizontal hoops are tiltably pivoted to seesaw

2

through short arcs. The hoops lie across the hip section of the mannequin and are designed to form the outline of the hips of the mannequin. The oscillation of the sliding assembly causes the hoops to move horizontally across the axis of the mannequin body as well as the seesaw. With this horizontal oscillation, the hoops tilt on their pivoting supports. This pivoting causes the hoops to converge at one side of the mannequin body while they are separating at the other end to alternately separate at the first side while they are converging at the second.

The mechanism within the mannequin body also provides a swivel connection mounted on the crank linkage and rotated by it. The rotary motion of this swivel connection in turn provides a yoke in the shoulder section of the mannequin with an oscillating motion. Thus, as the hoops oscillate and seesaw, the shoulder yoke is simultaneously pivoted on its axis to rotate back and forth through a short arc. The mannequin is covered with simulated clothing over the flexible material making up the hollow casing of the body. This clothing reacts to the movements of the body casing brought about by the actuating mechanism to produce a simulation of lifelike motions.

An embodiment of this invention is shown in the accompanying drawings. Referring to Fig. 1, a mannequin 10 is shown mainly in section and composed of a flexible material moulded into thin walls 11 forming a body having a hollow interior 12. The mannequin 10 is mounted on a turntable 13 which in turn is supported through a hub 14 on a platform 15 containing a motor 16 and two sets of chains and sprockets. The motor 16 turns dual sprockets 17 and 18. Sprocket 17 drives a larger sprocket 19 through a chain 20 while sprocket 18 drives a smaller sprocket 21 through a chain 22. The sprocket 19 has mounted on it an axle 23 and is supported in a journal 24 which is hung from the inner surface of the top of the platform 15. The hub 14 in turn is mounted on the upper end of the axle 23 which, driven by the sprockets 17 and 19 and chain 20 rotates in journal 24 to rotate the hub 14, the turntable 13 and the supported mannequin 10. Simultaneously and independently, the sprocket 21 through sprocket 18 and chain 22 is driven to rotate a shaft 25 vertically mounted thereon. The shaft 25 is extended upward from the sprocket 21 through passages in the axle 23, the hub 14 and the platform 15 and the turntable 13 to a leg 26 of the mannequin. A hollow pole 27 mounted on the turntable 13 extends upward through the hollow interior of the leg 26 entering the leg through an aperture in the foot portion. The shaft 25 is encased inside but moves independently of

the pole 27. The shaft 25 and the pole 27 terminate at the hip section of the mannequin 10.

As shown in Fig. 2, the hip section of the mannequin 10 contains a cruciform member 28 shown also in perspective in Fig. 8. Referring again to Fig. 2, it is seen that the cruciform member 28 has a central slide 29 containing a central slot 30. The cruciform member 28 is also provided with a pair of crossarms 31, the upper of which is seen in Fig. 2. The crossarms 31 are joined together at their extremities by vertical plates 32 as shown in Fig. 8. Referring to Fig. 3, it is seen that the pole 27 has fitted on its upper end a horizontally extending arm 33, the upper surface of which forms a platform 34. The slide member 29 rests on or is adjacent to the platform 34. The shaft 25 protrudes a short distance from the upper end of the pole 27. The upper end of the shaft 25 is encircled with a recess 35 which receives a link 36 fitted and pivotally held thereon. The recess 35 is formed in the shaft 25 at a point just above the position of the slide member 29 on the platform 34 so that the link 36 may move independently of the slide 29 through an angle of 360° as seen in Figs. 1 and 2, 6 and 7. The link 36 is thus rotatable to any position. In the opposite end of the link 36 from the indented recess 35, a crankpin 37 is securely mounted extending upwardly parallel to the axis of the pole 27 and the shaft 25. The crank pin 37 is in turn girdled with a recess about halfway up its vertical dimension and holds another link 38. A pin through the opposite end of the link 38 from the pin 37 supports the upper crossarm 31 on the link 36. As the upper crossarm of the cruciform 28 is integral with the slide 29 through the plates 32 and lower crossarms 31 as shown in Fig. 8, the cruciform 28 as a whole is supported on the shaft 25 through the link 36, the crankpin 37 and the link 38 as seen in Fig. 3. The end of the shaft 25 which protrudes from the pole 27 extends through the slot 30 of the slide member 29 but does not engage it so that the slide is free to move with relation to the shaft in a crosswise direction as seen in Fig. 3.

As seen in Fig. 4, the links 38 and 36 are lined up in line with the slot 30 and the pin 37 is centered directly over the slot 30. A rod 39 supported at the outer end of the arm 33 as seen in Fig. 3 is at the extreme left end of the slot 30 in the position shown in Fig. 4. Figs. 2 and 6 are top views of the slide assembly shown with the front facing the bottom of the sheet. In Fig. 6, the linkage formed by links 36 and 38 is shown in half extended position with the rod 39 positioned in the slot 30 halfway toward the crossarms 31. In Fig. 2, the linkage of links 36 and 38 is shown in fully extended position and the rod 39 is adjacent crossarms 31.

A hoop 40 is supported on the cruciform 28 being attached at each side at the upper end of the plates 32 by a pin 41 to permit a free tilting movement. Similarly, the hoop 42 is supported on the cruciform 28 being fastened at each side by pins 43 to the lower ends of the plates 32 as shown in Fig. 1. The hoop 42 is also freely tiltable on its attaching pins 43.

The rod 39 extends upwardly from the arm 33 through the slot 30 to a point in the shoulder section of the mannequin 10. The upper end of the rod 39 supports a bracket 44 which extends horizontally across the hollow interior 12 of the mannequin 10 and is centrally provided with a hub 45 into the hollow center of which is fitted a bushing 46. At the end of the bracket 44 oppo-

site from the rod 39 a ball socket 47 is suspended by a bolt 48 which is fastened to the bracket 44. The ball socket 47 contains a ball end 49 of a swivel rod 50, the other end of which is formed into a second ball end 51 which seats in a socket 52 recessed in the upper end of the crankpin 37.

Swiveling on the flat upper surface of the hub 45, a yoke 53 is formed to have shoulder portions 54 and a neck portion 55. The yoke 53 has a downwardly extending shaft 56 centrally positioned in its underside. The shaft 56 passes rotatably through the bushing 46 and extends downwardly parallel to the rod 39 and adjacent the swivel rod 50. At a point adjacent the upper end of the swivel rod 50, the shaft 56 has mounted on it a fork 57 by means of a collar 58. The fork 57, as seen in Fig. 5, has two horizontally extending prongs 59 extending in the direction of and engaging the swivel rod 50 in a slot 60 between the prongs 59. The collar 58 is fixed on the shaft 56 so that the shaft 56 and its mounted yoke 53 move with the motion supplied to the fork 57 by the swivel rod 50. The casing walls 11 of the mannequin 10 are parted at the hip section by a gap 61 which divides the mannequin into upper and lower parts.

In the operation of this embodiment of this invention, the motor 16 is energized to turn the sprockets 17 and 18 and through chains 20 and 22 the sprockets 19 and 21 respectively. The sprocket 19 turning axle 23 moves the hoop 14 and its superimposed platform 15 upon which the mannequin 10 stands. Thus, the mannequin is made to rotate with the platform 15. At the same time, the sprocket 21 drives the shaft 25 which is inside of the hollow pole 27 as best seen in Fig. 3. As described above, the shaft 25 rotates the link 36 which, in turn, carries the vertical crankpin 37 at its free end and through this crankpin 37 swings the free end of the link 38 from side to side through a semi-circle. The free end of the link 38 is attached to the crankpin 37 and the fixed end of the link 38 is anchored by a pin 63 to the center of the crossarm 31 of the cruciform 28. The free end of the link 38 thus swings back and forth through a semi-circular arc while the fixed end oscillates along a line with the oscillating cruciform 28. The oscillating motion of the cruciform 28 is provided by the rotating link 36 as transmitted to the cruciform 28 through the swinging link 38. The cruciform 28 riding on the platform 34 is held in line by the pole 27 and the rod 39 acting as pins sliding in the central slot 30. The reciprocation of the cruciform 28 is transmitted to the hoops 40 and 42 through the plates 32. The hoops 40 and 42 thus oscillate back and forth horizontally across the vertical axis of the mannequin 10. For the purpose of this description, the position of the hoops 40 and 42 when swung to the right, as seen in Fig. 1 or from the front, is termed the dexter position and correspondingly to the left will be termed the levular position.

The mannequin 10 is covered with a cloth 62 made up to simulate clothing. This cloth covering covers the gap 61 in the hip section of the mannequin. As the hoops 40 and 42 are swung from one side to the other they seesaw on their pivot pins 43. The plates 32 also move from side to side. When the plates 32 move the hoops 40 and 42 to an extended position at one side of the mannequin 10, the flexible material 11 at that side tends to pull the hoops away from each other in a vertical plane while the wall material 11 at the other side tends to push the

5

hoops together in a vertical plane. Upon the reverse motion of the sliding assembly and the movement of the plates 32 carrying the hoops 40 and 42 to an extended position toward the other side, the opposite effect is obtained. Thus, as shown in Fig. 1, the hoops are shown in the dexter position separated at the right side and converged at the left side. When the plates 32 and the hoops 40 and 42 are in central position as shown in Figs. 6 and 7, the hoops are substantially parallel to each other. In every complete cycle, the sliding assembly and the crank linkage together with the hoops pass through the central position twice. Also, during each complete cycle, the hip actuating mechanism is extended once fully to the dexter position and once to the levular position. In Fig. 1, the hip actuating mechanism is shown in full dexter position. In Fig. 3, the hip actuating mechanism is shown in full levular position. In Figs. 6 and 7 the hip actuating mechanism is shown in one of the two central positions.

The operation of the shoulder actuating mechanism is simultaneous and coordinated with the operation of the hip actuating mechanism. The operation of the shoulder actuating mechanism is brought about by the rotation of the link 36 as translated through the crankpin 31, the swivel rod 50 and the shaft 56 through the fork 57. The swivel rod 50 is shown in one position in Fig. 1 and in another position in Fig. 3. In being moved through these positions by the link 36 and the crankpin 31, the rotation of the swivel rod 50 describes the surface of a cone with the ball end 51 forming the apex of the cone and the ball end 49 describing the base of the cone. By thus rotating, the rod 50 translates a reciprocating motion to the fork 57 which engages it with prongs 59. This reciprocating motion is translated into a reciprocating motion of the shaft 56 which turns the shaft 56 back and forth on its axis for short rotational movements. The yoke 53 in turn is provided short back and forth rotational movements and thus provides the shoulder section of the mannequin 10, the wall of which it touches, with movement.

The clothing 62 is affected both by the hip actuating mechanism through its effect on the wall material 11 of the mannequin 10 and the shoulder actuating mechanism through the effect on the wall material 11 of the mannequin 10. The shoulder yoke 53 engages the inner surface of the shoulder of the mannequin 10 and moves backward and forward along this inner surface for describing short arcs. The wall material 11 is provided with freedom to permit the transmission of the motions of the actuating mechanism to the covering material 62 through the wall material 11 with the greatest efficiency. Consequently, as described above, side apertures 61 are provided in the hip section by the hoops 40 and 42. Similarly, the bust section of the wall material 11 may be suitably apertured to provide a lifelike freedom of the wall material 11.

It is a feature of this invention that a lifelike motion is provided a display mannequin by a simple rugged mechanism having a reliable mode of operation. It is another advantage of this invention that the motion supplied to the body of the mannequin may be adjusted by arrangement of the parts to provide a variety of interpretations of lifelike body movement.

Various modifications of the embodiment of this invention shown and described herein may

6

be made without departing from the spirit of the invention. For this reason, it is intended to limit this invention by the scope of the appended claims.

We claim:

1. An animated figure comprising a flexible hollow casing simulating a human form including an upper hollow body portion forming a simulated human trunk, arms, shoulders, neck, and head portions; a lower hollow body portion composed of feet, legs, and lower hip portions; a lower edge encircling and terminating said upper body portion, an upper edge terminating and encircling said lower body portion adjacent to but spaced from said lower edge of said upper body portion; a first hoop positioned within and contacting said lower edge, a second hoop positioned within and contacting said upper edge, a reciprocable integral cruciform positioned within said casing, a cross arm on said cruciform pivotably supporting said hoops at their outer ends, shaft and link means attached to said cruciform, and means driving said shaft and link means to cause said cruciform to reciprocate whereby said pivotably mounted hoops are oscillated and said contacted casing is provided an oscillatory motion.

2. An animated figure of the type set forth in claim 1 including a vertical plate at each end of said cross arm on which said hoops are pivoted, a rotatable shaft in said shaft means, a fixed platform mounted adjacent the upper end of said rotatable shaft, a rotatable end of said shaft protruding through said platform, a body portion of said cruciform slidable on said platform, a central slot in said cruciform body receiving said rotatable upper end of said shaft, and a pair of links attaching said rotatable shaft end to said cross arm whereby rotation of said shaft causes said links to reciprocate said cruciform on said platform and to reciprocate said vertical plates which, in turn, oscillate said pivotably mounted hoops.

3. An animated figure of the type set forth in claim 1 including a swivel rod, a crank pin rotatably mounted on an end of said shaft means receiving one end of said swivel rod, a reciprocable fork engaged by said swivel rod, a shaft supporting said reciprocable fork and fixed thereto, and a yoke positioned in the shoulder portion of said upper body portion mounted on said shaft and contactable with said casing in said shoulder portion whereby rotation of said rotatable crank pin and said swivel rod reciprocates said fork, shaft and yoke to engage and disengage said yoke with said casing in the shoulder portion.
